US00D776649S

(12) **United States Design Patent** (10) **Patent No.:** **US D776,649 S**
(45) **Date of Patent:** **** Jan. 17, 2017**

(54) **CASE FOR ELECTRONIC DEVICE**

(71) Applicant: **Spigen Korea Co., LTD.**, Seoul (KR)

(72) Inventor: **Dae-Young Kim**, Seoul (KR)

(73) Assignee: **SPIGEN KOREA CO., LTD.**,
Geumcheon-gu, Seoul (KR)

(**) Term: **15 Years**

(21) Appl. No.: **29/569,932**

(22) Filed: **Jul. 1, 2016**

CLAIM

The ornamental design for a case for electronic device, as shown and described.

DESCRIPTION

FIG. 1 is a front perspective view of a case for electronic device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view thereof with a support leg extended;

FIG. 10 is an exploded rear perspective view thereof;

FIG. 11 is a front perspective view of the inner shell of the case;

FIG. 12 is a rear perspective view of the inner shell of the case;

FIG. 13 is a front perspective view of the support leg of the case;

FIG. 14 is a rear perspective view of the support leg of the case;

FIG. 15 is a front perspective view of the outer frame of the case; and,

FIG. 16 is a rear perspective view of the outer frame of the case.

The broken line in the figure drawings represents unclaimed environment only and forms no part of the claimed design.
